WINDOW LATCH HANDLE

Forrest F. Beil, Clinton, Iowa, assignor to Curtis Companies Incorporated, Clinton, Iowa, a corporation of Iowa

Application April 25, 1955, Serial No. 35,646

Term of patent 14 years

(Cl. D10—8)

FIG. 1

I claim:

The ornamental design for a window latch handle, substantially as shown.
